UNITED STATES PATENT OFFICE

SILAS M. RATZKOFF, OF JACKSON HEIGHTS, NEW YORK, ASSIGNOR TO TROY LAUNDRY MACHINERY COMPANY, INC., OF EAST MOLINE, ILLINOIS, A CORPORATION OF DELAWARE

IDENTIFICATION PIN HOLDER FOR WASHING MACHINES

Application filed June 18, 1930. Serial No. 461,914.

The invention relates to washing machines and has reference more particularly to a novel identification tag holder for association with washing machines.

5 The type of washing machines employed in the present day laundries are constructed with a revolving cylinder which is divided into a plurality of compartments or pockets, each pocket being designed to handle an individual family washing. During the various operations of washing, drying and ironing done upon the clothes, it is customary to contain each family washing in a bag in which same is transported from one machine to another. The opening of each bag is held closed by a suitable pin to which is attached a tag or some suitable marker having a number to correspond with the number assigned to the particular bundle, the marker remaining with the goods during the whole laundry process.

10 Heretofore it has been generally the practice when placing the clothes in the cylinder pockets to either hang the pin and tag attached thereto on some convenient hook or to place the same in a small container provided on the inside of the cylinder pocket. However, objectionable features exist in the use of the small container located on the inside of the cylinder pocket, in that the container offers obstructions which are apt to tear the garments being washed. To this end one of the objects of the present invention is to provide a novel holder for supporting the pin and attached tag in convenient position on the exterior of each cylinder pocket, thus obviating the possibility of any mix-up in the identification of the clothes during the laundry operations.

15 A further object is to provide a holder designed to be riveted or otherwise secured to the sliding cylinder door and which will be capable of allowing easy insertion and removal of a pin and identification tag.

20 A yet further object of the present invention is to provide a holding device having slots and uprights so disposed with each other that the pin and tag after insertion will be held from movement in all possible

A still further object is to provide a holding device adapted to be stamped or formed from a single sheet of metal and which will be so designed as to utilize the resiliency of the pin for holding the pin and tag in place.

25 With these and various other objects in view, the invention may consist of certain novel features of construction and operation, as will be more fully described and particularly pointed out in the specification, drawing and claims appended hereto.

30 In the drawing, which illustrates an embodiment of the device and wherein like reference characters are used to designate like parts—

35 Figure 1 is an elevational view of a washing machine showing the same equipped with the holder of the present invention;

40 Figure 2 is an enlarged fragmentary plan view showing the pin and the identification tag in position in the holder;

45 Figure 3 is an elevational view of the same; Figure 4 is a perspective view of the holder; and

50 Figure 5 is a perspective view showing the type of pin with identification tag attached, adapted to be inserted in the holder.

55 The holder of the present invention is primarily adapted for association with washing machines of the type wherein it is desirable to locate in convenient position a pin and identification tag. However, it is obvious that such holders could be of different shapes and also could be associated with various types of machines and still perform the same function.

60 Referring to the drawing, Figure 1 shows a general type of washing machine 10 having supporting pedestals 11 and a substantially cylindrical casing or drum 12. Rotatably mounted within the drum on trunnion sockets 13 is a cylinder 14 divided into a plurality of compartments or pockets 15; each pocket being opened and closed by a sliding door 16. The door is raised to allow access to the interior of the pocket so that the family wash located therein can be removed and another bundle of clothes inserted. After the various pockets are filled and the doors 16 closed, the cover 17 of the main casing 12 is

closed and the cylinder 14 revolved by any suitable form of power, such as electric motor 18.

As the various pockets are filled with an individual family washing it becomes necessary to locate in convenient position to the pocket the pin having the identification tag attached thereto, which pin was used to close the bag containing the clothes. For this the present invention contemplates a novel form of holding device adapted to be formed or stamped from a single blank of metal and which comprises a base 20 having openings 21 for securing the holder in position on the sliding door 16, preferably immediately above the handle 22. The base is provided at one end with side portions 23 each portion having a horizontally disposed slot 24 and a rounded extremity 25. On the other end of the base 20 the same is provided with a lip 26 which is slotted at 27 to form the upstanding positioning lug 28. Located inwardly from the lip the base is formed with uprights 30 on either side thereof which are provided with inbent portions 31, said uprights constituting opposing clips.

The holder described has been designed for a particular shape and size of pin but it is to be understood that the invention is not necessarily limited to the size and arrangement of parts shown. The pin is of the ordinary safety pin variety having a back portion 32 with a clasp 33 at one end and a loop 34 at the other. The prong 35 is resilient and is secured in closed position by clasp 33. A ring 36 serves to secure the identification tag 38 to the pin.

For inserting the pin and tag in the holder it is only necessary for the operator to hold the pin allowing the tag to hang free. The looped end 34 of the pin is then located between the portions 23 and moved in a direction to hook the tag in the slots 24. With the tag held in place the free end of the pin is moved downward to engage the clips 30, which function to lock the pin and tag to the holder.

With the holder secured in position on the sliding door 16 by rivets 40, it will be seen that by the construction of the horizontal slots 24 and clips 30 that the pin and tag may be easily inserted into and removed from the holder. This insertion is facilitated by reason of the rounded ends 25, which allow the operator to hold the pin and hook the tag 38 readily within the slots.

Also, it is to be noted that the uprights 30 are so located on the base that with the tag in position within the slots 24, the clips will engage the back 32 and prong 35 of the pin, thus locating the resilient portions of the pin in position to be engaged by the inbent portions 31. The resiliency of the pin is in this manner employed for holding the pin in the

holder. The uprights of course also function to prevent movement of the pin in a direction sidewise, while the lug 28 engaging the clasp 23 prevents movement of the pin endways.

It is to be understood that I do not wish to be limited by the exact embodiment of the device shown, which is merely by way of illustration and not limitation, as various and other forms of the device will of course be apparent to those skilled in the art without departing from the spirit of the invention or the scope of the claims.

I claim:

1. In a device of the character described, the combination of a pin and tag attached thereto, of a holding device for releasably holding said pin and tag in extended position, one end of said device having means for holding the tag in position and the other end having uprights resiliently engaging the pin.

2. In a device of the character described, the combination with a pin and tag attached thereto, of a holding device for releasably holding said pin and tag in extended position, one end of said device having slots for accommodating the tag, and the other end having uprights resiliently engaging the pin.

3. In a device of the character described, the combination with a pin and tag attached thereto, of a holding device for releasably holding said pin and tag in extended position, one end of said device having slots for accommodating the tag, the other end being provided with uprights and a positioning lug for engaging and positioning the pin.

4. A holding device for a pin having a tag attached thereto, said holding device comprising a base, side portions formed on said base at one end thereof, horizontally disposed slots provided in said side portions to engage and hold said tag, and clips formed upon the base at the other end thereof for gripping the pin.

5. A holding device of the character described comprising a base, side portions formed on said base at one end thereof, horizontally disposed slots provided in said side portions, the opposite end of said base being raised to form a lip portion, a positioning lug located at the base of said lip, and uprights provided on the sides of said base in the vicinity of said lip portion.

6. A holding device of the character described adapted to be stamped from a blank of metal comprising a base, side portions integral with said base and upstanding therefrom, slots located in the side portions, and uprights integral with the base and located at the end opposite the side portions, the extremities of the uprights being inbent to form gripping members.

7. A device for holding an article including a pin and tag attached thereto, said de-

vice comprising a base, side portions provided on said base at one end thereof, horizontal slots in said side portions for accommodating the tag, a raised lip portion provided at the other end of the base, a positioning lug located adjacent the lip portion, and uprights located on the sides of said base, said uprights adapted to hold said pin while the lip portion and lug position the pin.

5 10 Signed at Jackson Heights, New York, this 28th day of May, 1930.

SILAS M. RATZKOFF.
